RIFLING MACHINE

Henry E. Durkee, Manchester, Conn., assignor to
 Niles-Bement-Pond Company, West Hartford,
 Conn., a corporation of New Jersey

Application April 22, 1940, Serial No. 330,862

5 Claims. (Cl. 90—28.1)

This invention relates to rifling machines and more in particular to a rifling machine for shoulder muskets and similar small arms.

An object of the invention is to provide an improved form of rifling tool advancing and rotating means, the tool of which operates upon a gun barrel supported on the machine and maintained in fixed position during the movements of the rifling tool.

A feature which enables me to accomplish the above object is that the rifling tool is held upon a spindle rotatably mounted within a slideable carriage, the carriage being movable along the machine bed in a direction coaxial with that of the barrel being rifled. While being advanced the spindle within the carriage is rotated in predetermined relation to its advancing movement by means of a nut engaging a spirally grooved member connected by suitable gearing to the tool spindle.

Another object of the invention is to mount the spirally grooved member in a direction parallel to and in fixed position at one side of the slideably mounted carriage so that the overall length of the machine may be reduced to the shortest practicable length.

With the above and other objects in view the invention may include the features of construction and operation set forth in the following specification and illustrated in the accompanying drawings.

In the accompanying drawings annexed hereto and forming a part of this specification, I have shown the invention embodied in a gun barrel rifling machine for shoulder muskets, but it will be understood that the invention can be otherwise embodied and that the drawings are not to be construed as defining or limiting the scope of the invention, the claims appended to this specification being relied upon for that purpose.

In the drawings:

Figure 1 is a front elevation of a complete machine partly broken away in which the present invention is incorporated.

Fig. 2 is a plan view of the machine shown in Fig. 1.

Fig. 3 is an end elevation of the machine shown in Figs. 1 and 2.

Fig. 4 is a horizontal sectional view taken through the centers of the spirally grooved member and the rifling tool rotating spindle.

Fig. 5 is an end elevation, partly in section, taken on the line 5—5 of Fig. 4.

Fig. 6 is a longitudinal vertical section taken upon the plane of line 6—6 shown in Fig. 5, and 55

Fig. 7 is a diagram of the hydraulic connections of the machine for actuating the tool carriage longitudinally along the machine bed.

In the above-mentioned drawings there has been shown but one embodiment of the invention which is now deemed preferable, but it is to be understood that changes and modifications may be made within the scope of the appended claims without departing from the spirit of the invention.

Briefly and in its preferred aspect, the invention may include the following principal parts: First, a base having longitudinal horizontal ways extending substantially the entire length of the bed; second, means to support and periodically index one or more gun barrels, or other parts to be rifled; third, a tool carriage slidably mounted upon the ways and movable directly toward and from the member being rifled; fourth, a tool rotating spindle within the carriage, the axis of which is in alignment with the axis of the member being rifled; fifth, a helically grooved member fixed in position upon the base at one side of and parallel to the axis of rotation of the rifling tool; sixth, means engaging the rifled member and connected to the tool rotating spindle to rotate the spindle in timed relation to its forward movement.

Referring more in detail to the figures of the drawings, there is shown a complete embodiment of a duplex rifling machine in which the present invention has been incorporated.

Referring first to Figs. 1, 2 and 3 of the drawings, an elongated bed 10 suitably supported and having horizontal parallel ways 11 extending substantially its entire length, there being provided on the ways 11 adjacent one end of the machine a work holding chuck 12. This chuck or work holding member 12, as shown, may be mounted upon a carriage 13 fixed in position on the ways 11 of the bed 10 and provided with indexing means (not shown) so that the chuck 12, together with the member being rifled W, may be indexed periodically during the rifling operation. Also at one end of the machine is a tool feeding device 14 for adjusting the radial position of the rifling tool within its cutter head and at an intermediate position is a steady rest 15 for the outer or free end of the member W being rifled. As these parts are or may be similar to those now found in standard forms of rifling machines, it is not thought that any further description will be necessary. It will suffice to state that the gun barrel W, or other part to be rifled, is mounted horizontally and centrally of the ma-

chine ways 11 and is indexed between successive movements of the rifling tool by appropriate means forming no part of the present invention.

Adjacent the opposite end of the machine from the chuck 12 is a tool reciprocating slide or member 16 having a spindle 17 rotatably mounted therein and disposed coaxially to the axis of rotation of the member W to be rifled. This spindle 17 is provided with a gear 18 secured directly thereto in mesh with a gear 19 on a rotatable member 20 parallel to the spindle 17. On this latter member 20 is a nut 21 mounted for convenient removal and substitution and adapted to engage the grooves of a helically fluted member 22. This helically fluted member 22 is, as shown in Figs. 1 and 2, mounted in fixed position on the base 10 within suitable brackets 23, one of these brackets 23 being at each end of the member and serving to retain the member 22 against rotation and endwise movement. This fluted member 22 is disposed exactly horizontally and parallelly with the rifling tool spindle 17 and as the carriage 16 carrying the spindle 17 reciprocates the nut 21 will be rotated in accordance with the helix of the grooves on member 22 and will correspondingly rotate the rifling tool spindle 17 through the gears 18 and 19 connecting the spindle 17 and member 20.

In order to control the movements of the tool supporting carriage 16 there may be provided a cylinder 24 fixed to the base 10 below the ways 11 within which a piston 25 may reciprocate. This piston 25 by means of its piston rod 26 extending from one end of the cylinder, engages a dependent portion 27 of the tool carriage 16. By means of a hydraulic system of conventional type a liquid may be forced into one or the other end of the cylinder 24 to advance the carriage 16 in either direction. In order to accomplish this movement the following control system may be employed. An actuating rod 28 parallel to the direction of carriage movement and slidably mounted upon the ways 11 is provided with adjustable collars or dogs 29 adjustable to any positions along the rod 28. These dogs or projections 29 are in the path of the movement of the carriage 16 and form reversing means for this carriage by being axially moved by the carriage. Movement of this rod 28 actuates a cam member 30 in one direction or the other and oscillates a T-shaped member 31, one arm of which is attached to a controlling valve 32. Movement of the control valve 32 to one or the other of its operative positions causes fluid under suitable pressure to be admitted to a distributing valve 33, the function of the control valve 32 being only to operate the distributing or reversing valve 33 at the predetermined end positions of the movement of the tool slide or carriage 16. With this distributing valve 33 in either of its extreme positions fluid under pressure will be admitted to one end or the other of the cylinder 24.

It will be seen from an inspection of Fig. 4 that the tool spindle 17 for the rifling tool is provided at one end with a suitable chuck or tool mounting means 34 which positively locks the tool in position for rotation with the spindle 17. It is essential in rifling operations that all lost motion between parts of the mechanism be eliminated in order that each successive groove in the member W being rifled may be uniform and at the proper angular distance from the other grooves. In order to eliminate or control the lost motion in the driving and rotating means for the rifling tool, a spirally wound spring 35 is housed within

the carriage 16, one end of which is attached in any suitable manner to a part of the rotatable mounting for the spindle 17 and the opposite end is attached to a fixed flange or collar 36 within 5 the tool carriage 16. From this construction it will be evident that during rotating movements of the tool spindle 17 while the carriage 16 is moving the spiral spring 35 will be partially wound and unwound, thus at all times maintaining a pressure in one direction of rotation of the spindle 17. By means of this spring 35, therefore, the spindle 17 is always held as far as possible in one direction and with the lost motion between the driving members for the spindle 17 10 on the same side.

What I claim is:

1. A rifling machine comprising in combination, a base having guideways thereon, means to support a gun barrel on said base with its axis parallel to said ways, a carriage slidable along said ways, a tool supporting and rotating spindle within said carriage, a helically splined member secured in a fixed position to said base parallel to said ways, a nut engaging said splined member, gear connections between said nut and tool spindle whereby movement of said tool carriage along said ways effects simultaneous axial and rotative movement of said tool, and a helical spring having one end fixed relative to said carriage and its opposite end mounted on and for rotation with said tool spindle, whereby said spindle is normally forced in one direction of rotation.

2. A rifling machine comprising in combination, a base having guideways thereon, means to support a gun barrel on said base with its axis parallel to said ways, a carriage slidable along said ways, a tool supporting and rotating spindle within said carriage, a helically splined member secured in a fixed position to said base parallel to said ways, connections between said splined member and tool spindle whereby movement of said tool carriage along said ways effects simultaneous axial and rotative movement of said tool, and a helical spring having one end fixed relative to said carriage and its opposite end mounted on and for rotation with said tool spindle, whereby said spindle is normally forced in one direction of rotation.

3. A rifling machine comprising in combination, a base having guideways thereon, means to support a gun barrel on said base with its axis parallel to said ways, a carriage slidable along said ways, a tool supporting and rotating spindle within said carriage, a helically splined member secured in a fixed position to said base parallel to said ways, driving connections between said splined member and tool spindle whereby movement of said tool carriage along said ways effects simultaneous axial and rotative movement of said tool, and a helical spring surrounding said tool spindle and winding and unwinding with rotative movements of said spindle in opposite directions.

4. A rifling machine comprising in combination, a base having guideways thereon, means to support a gun barrel on said base with its axis parallel to said ways, indexing means for said gun barrel within said supporting means, a carriage slidable along said ways, a tool supporting and rotating spindle within said carriage, a helically splined member secured in a fixed position to said base parallel to said ways and at one side of said carriage, driving connections between said splined member and tool spindle whereby movement of said tool carriage along said ways effects simultaneous axial and rotative movement of said tool, and a helical spring hav-

ing one end fixed relative to said carriage and its opposite end mounted on and for rotation with said tool spindle, whereby said spindle is normally forced in one direction of rotation.

5. A rifling machine comprising in combination, a base having guideways thereon, means to support a gun barrel on said base with its axis parallel to said ways, indexing means for said gun barrel within said supporting means, a carriage slidable along said ways, a tool supporting 10 and rotating spindle within said carriage, a heli-

cally splined member secured in a fixed position to said base parallel to said ways and at one side of said carriage, a nut on said splined member, and gears connecting said nut and tool spindle whereby movement of said tool carriage along said ways effects simultaneous axial and rotative movement of said tool, and means normally forcing said tool spindle in one direction of rotation.

HENRY E. DURKEE.
